UNITED STATES PATENT OFFICE.

BENSON P. COOPER, OF ITHACA, NEW YORK.

COIN-CONTROLLED DELIVERY APPARATUS.

Original application filed October 18, 1917, Serial No. 197,363. Divided and this application filed January 22, 1919. Serial No. 272,500.

To all whom it may concern:

Be it known that BENSON P. COOPER, a citizen of the United States, and resident of Ithaca, in the county of Tompkins and 5 State of New York, has invented a new and useful Improvement in Coin-Controlled Delivery Apparatus; and he does hereby declare the following to be a full, clear, and exact description thereof.

10 My invention relates to apparatus for delivering articles by means of coin-released mechanism, its object being to provide an apparatus of this character which is not liable to get out of order, and so simple in 15 construction that any difficulty arising in its use may be readily corrected without the employment of skilled labor.

To these ends my invention comprises the novel features hereinafter set forth and 20 claimed.

In the accompanying drawing Fig. 1 is a vertical side elevation of my improved apparatus, the container for the article to be sold being broken away; Fig. 2 is a vertical 25 section of my improved apparatus; Fig. 3 is a like view, showing dotted line positions of the different parts; Fig. 4 is a sectional view taken on the line 4—4 Fig. 1; Fig. 5 is a view of the end of the cylinder, and Fig. 30 6 is a cross-section of the solid end of the cylinder taken through the slot.

In the drawing the numeral 2 designates the casing which encloses the operating parts, and to which is connected the chute 3 35 for containing the articles to be sold, the articles being delivered therefrom to the delivery trough 4 which is cylindrical in form with the opening 5, to permit of the discharge of the article therefrom when 40 said delivery trough is turned in the manner more fully hereinafter set forth. This delivery trough 4 is mounted to oscillate, and is provided with the trunnions 6 engaging suitable bearings 7 in the casing 2.

45 A sheave-portion 8 is formed integral with the trough, although it may be connected if desired, and may be separate therefrom. The sheave-portion 8 is provided with the groove 9 which forms a guide or bearing for the coiled spring 10, one end of said spring being connected to the web 11 in the groove 9 of said sheave 8, while the other end of said spring is connected as 50 at 13 to the inside wall of the casing 2.

An operating handle 14 is connected to 55 one of the trunnions 6 for turning the delivery trough 4.

The end-plate 15 of the delivery trough has the slot 15^a engaging the stud 16 on the casing 2, said stud acting as a stop to control the oscillatory movement of the delivery trough. The plate 15 is provided with the shoulder 17 which is adapted to engage one end 18 of the dog 19, said dog being pivoted at 20 to the casing 2. A spring 21 connected to the dog 19 bears with its free end against the abutment 22 in the casing and normally holds said dog down in locking position. The one end 18 of this dog being in the path of the shoulder 17 of the 60 end plate 15, when the handle 14 is moved the shoulder 17 will engage with the lower end 18 of the dog 19, and further movement of the plate 15, and consequently of the delivery trough 4, is prevented so that the 65 delivery trough cannot be operated to discharge an article therefrom until freed by the coin as will more fully hereinafter appear.

In order to prevent tampering with the 70 locking dog 19, and lifting it out of the way so as to permit the movement of the delivery trough without the insertion of a coin, I provide a guard 23, which consists of an inwardly extending flange on the casing 75 which extends in under the dog 19 and prevents any one from lifting the dog by the insertion of a wire or other instrument to release the delivery trough and permit its being turned so as to deliver an article therefrom without the insertion of a coin. The coin receiver 24 has the slot 25 which registers with the vertical slot 26 that extends completely through the plate 15. Below the plate 15 in the casing is the 80 money drawer 27.

The coin receiver 24 is extended up to such height that the front end of the dog 19 cannot be reached by a wire or other instrument inserted in the slot 25, it being 85 apparent as shown in Fig. 2 that any such instrument when inserted at the extreme angle permitted would not be able to reach the end 18 of the dog 19 to lift same.

The slot 26 in the plate 15 is flared to 90 form a seat 29 at the upper end of said slot to receive the coin. Coins of smaller denomination than that required to operate 95

the machine will pass down through the slot 26 and no operation of the machine results from the use of such small coins.

In the operation of the apparatus the 5 coin is introduced into the slot 25 of the coin-receiver, and said coin passes down and seats itself in the flared seat 29 at the upper end of the slot 26 in the plate 15. The operating lever 14 is then moved down- 10 ward and the coin 30 projecting beyond the periphery of the plate 15, will engage the outer end of the dog 19 and said dog will ride up over the periphery of the coin, and will be lifted so as to permit the coin to 15 pass and the delivery trough to be rotated sufficiently to deliver the article contained therein down into the lower end of the casing to be removed from the opening 31. The movement of the operating arm 14 is 20 controlled by the end of the slot 15^a coming into contact with the stud 16, and during this movement the spring 10 is extended as shown in Fig. 3. When the delivery trough has been brought into position to 25 deliver the article therefrom, the flared end 29 of the slot 26 will have moved around in such position as shown in dotted lines Fig. 3 to discharge the coin into the money drawer 27. Upon releasing the operating 30 lever 14, the spring 10 will throw the delivery trough back into normal position, as well as the plate 15, and the spring 21 will throw the dog 19 down again into locking position. In such position if anyone at- 35 tempts to operate the machine without a coin by moving the lever 14, the shoulder 17 will come into engagement with the end of the dog 19 and prevent movement of the delivery trough. 40 By having the slots 25 and 26 in alignment with each other, the apparatus may

be readily cleaned or relieved of any plug or obstruction without removing the machine from the wall to which it is ordinarily secured. By simply opening the money 45 drawer the attendant may force a thin piece of steel up through these registering slots and remove any obstruction in the slot—such as tin, tacks, paper hair-pins, etc.—whereas ordinarily with an apparatus of 50 this character an expert mechanic is required to do this work. A great saving is effected in this way in that the machine may be installed in isolated places where it is not possible or not economically possible 55 to employ an expert to look after the machines in such isolated localities.

This application is a division of an application filed by me on the 18th day of October 1917, Serial No. 197,363. 60

What I claim is:—

In coin-controlled delivery apparatus, the combination of a casing, an oscillatory delivery trough mounted therein and having a certain amount of free play, a grooved sheave portion carried by said trough, a spring having one end secured to said sheave portion within said groove, and having its other end connected to said casing, a trunnion adjacent to said sheave portion and extending beyond said casing, a handle rigidly secured to said trunnion, means for locking said trough beyond the extent of said free play, said trough having a curved slot, and a stop on said casing engaging 70 said slot.

In testimony whereof, I the said BENSON P. COOPER have hereunto set my hand.

BENSON P. COOPER.
